UNITED STATES PATENT OFFICE.

MAX ARTHUR MUELLER, OF BROOKLYN, NEW YORK.

MACHINE FOR UNRAVELING AND WINDING YARN.

1,176,776.

Specification of Letters Patent. Patented Mar. 28, 1916.

Application filed April 13, 1912. Serial No. 690,462.

To all whom it may concern:

Be it known that I, MAX ARTHUR MUELLER, a citizen of the United States of America, and residing in the borough of Brooklyn, in the county of Kings and State of New York, have invented certain new and useful Improvements in Machines for Unraveling and Winding Yarn, of which the following is a specification.

My invention relates to improvements in machines for unravelling and winding yarn and particularly to a machine adapted to unravel and spool the yarn from knit fabrics, the object of my invention being to provide apparatus for unravelling either flat or circular knit goods and simultaneously spooling the same so that the yarn is not only recovered but is recovered in spools or bobbins adapted to be placed at once in knitting machines for reuse.

In the accompanying drawings, Figure 1 is a side elevation of a machine embodying my invention in one form; Fig. 2 is a broken end elevation of the machine; Fig. 3 is a section on the line 2—2, Fig. 1; Fig. 4 is a section on the line 3—3, Fig. 1; Fig. 5 is an elevation and Fig. 6 a section on the line 6—6, Fig. 5 of a detail of the drive mechanism; Fig. 7 is a perspective of a detail; Fig. 8 is a perspective of a base plate for the bobbin; and Fig. 9 is a perspective of the bobbin with base plate attached.

The present machine is designed for the recovery of yarn from fabric which by reason of some defect therein, cannot be utilized for the purpose for which it was made and consequently, unless the yarn is recovered, must be discarded as waste. Waste of this character is often quite valuable, as for instance, in knit woolen sweaters, and manufacturers commonly resort to unravelling and spooling by hand in this class of goods in order that the yarn may be reused. This has been the universal practice so far as I am aware in connection with flat goods and the better classes of woolens, in which recovery of the yarn is consequently the most important, are now commonly knit flat. Heretofore it has been practically impossible to recover the yarn in double lock knit goods even by use of hand machines. In the present machine the yarn from such goods,

whether knit in flat or circular form, is recovered directly on bobbins or reels. If more than a single strand of yarn is used in each knitted course, the various strands may be, and preferably are, separately recovered.

The winding mechanism comprises a plurality of rotary drawing elements here shown as bobbin carriers 10, on the lower end of the spindle 11 of each of which is mounted a friction disk 12. A coöperating driving disk 13 radially adjustable on its spindle 14 across the face of the friction disk 12 is provided with a band pulley 15 and a boss 16 in which engages a fork from the shifting lever 17, pivoted at 18, by means of which the radial adjustment of the driving disk 13 is secured to the desired speed of the bobbin carrier is regulated. The handle end 70 of the lever 17 rests upon a cross bar 18^a notched at 19 to receive the lever and hold the latter in adjusted position. The driving band 20 passes from pulley 15 to pulley 21 which is loose on the main driving shaft 75 22, but normally held in frictional contact with the juxtaposed clutch disk 23 fast on said shaft, by the light controller rod 24, pivoted at 24^a. The latter acts upon this pulley 21 through an overbalanced lever 25 pivoted at 26 and engaging the boss 27 on the pulley with a fork 28 at one end, while the other and free end 30 overlies and is supported by the rod 24. When this supporting end of the rod 24, which is pivoted 85 at 24^a, is lowered in a manner about to be described, the overweighted end 30 of the lever 25 tends to follow it, with the result that the pulley 21 is shifted on the shaft 22 out of its frictional engagement with the 90 clutch disk 23 and the drive of the bobbin thus halted. The pulley 21 is preferably provided with an annulus of friction material 31 on the face adjacent the face of the clutch disk 23 in order to insure a prompt 95 and efficient drive therefrom.

The yarn from the defective piece of goods 32, which is hung at 29 in stationary position during the operation of the machine, is passed directly from the goods to 100 a drag device 33, thence over a stationary guide 34 to an eye in the upper end of a light stop rod 35 jointed at its lower end to the end of the controller rod 24, and

finally to the guide finger 36 of the builder bar 37 which takes its motion from cams 38 on the auxiliary shaft 39 geared at 40 to the main driving shaft 22. The builder motion 5 is imparted to the builder bar 37 through the rods *a* on which the bar is supported from the ends of the rods *b* pivoted at *b*¹ and carrying at their opposite ends rollers *b*² upon which rest the ends of rods *c* pivoted at *c*¹ and bearing through rollers *c*² on the peripheries of the cams 38, against which they are held by the weight of the building bar. The drag device in the form shown 10 comprises a series of vertical rods 41 on which slide weighted curls 42 engaged by the yarn. When the piece of goods 32 is knit with several yarns the latter are preferably at once separated as they leave the goods and passed to independent drag curls 15 42 so that each of the latter acts upon a separate strand of yarn. Each strand is then separately passed over the guide 34, threaded through the eye of its own stop rod 35 and wound on a separate bobbin 43, 20 the speed of which is independently controlled as above explained.

The weight of the drag curl may be varied with the strength of the yarn in the piece 32; but in any event it is such that 25 should the yarn be caught in the piece (as for instance when turning the corner at one side of a piece of flat goods) the drag will rise on the rod 41 before the tension on the yarn becomes sufficient to raise the stop rod 35 and halt the drive. The continued pull upon the yarn during this rise of the drag, accompanied by a certain amount of resulting vibration of the thin rod, is sufficient in most instances to free the yarn at 30 the turn, so that the winding proceeds without interruption. Should the tension become sufficient to lift the long end of the stop rod 35, the drive of the bobbin is halted by the drop of the overbalanced lever and 35 resultant declutching of the friction pulley 21 from the clutch disk 23 before the yarn is broken. Brief attention by an attendant frees the yarn and the wind proceeds automatically by the return of the clutch to position upon the release of the tension which 40 has lifted the stop rod 35. Frequently personal attention is not needed, since the other strands which may have been at another portion of the course, overtake the position of 45 the halted strand during the winding of the slack afforded by the drag curl and the difficulty is automatically solved by the combined action of the various strands. When 50 unraveling circular knit goods very little or 55 no interruption in the operation of the apparatus is experienced. Should the tension upon the strand accidentally become sufficient to break the yarn, the bobbin of the particular broken strand spins harmlessly 60 on until the machine as a whole is halted by

the shifting of the main driving belt 44 by the lever 45. The broken yarn may be then repaired and winding proceeded with.

The apparatus shown is merely an illustrative embodiment of my invention. While 70 primarily intended for unraveling knit goods, it may be readily used for winding bobbins from skeins in which case a stand 46 carrying the usual skein rollers 47-48 may be placed in feed position. When 75 winding from skeins the yarn will ordinarily be so free that it may be passed directly to the guide 34 instead of through the drag device, but the latter may be used if desired. A metal base plate 49 with 80 radial pin engaging slot 50 and centering hole 51 may be fastened on the worn out base of a wooden bobbin by means of struck up tongues 52 or screws 53 whereby discarded bobbins may be utilized for the 85 present machine.

I claim as my invention:—

1. In an unraveling machine, a fabric support, a plurality of gravity drag devices for freeing the yarn therefrom, a bobbin carrier, means for driving the same, and means operatively engaged by the yarn between the drag devices and the bobbin for interrupting the drive upon excessive tension on the yarn. 95

2. In an unraveling machine, a fabric support, a plurality of gravity drag devices for freeing the yarn therefrom, a bobbin carrier, means for driving the same, a clutch device in the driving mechanism, a long 10 armed lever for opening the clutch and an operative connection between said lever and the yarn for moving the lever to open the clutch upon excessive tension on the yarn. 100

3. In an unraveling machine, a fabric support, a plurality of gravity drag devices for freeing the yarn therefrom, vertical rods on which said drag devices freely slide to take up varying feed from the fabric while maintaining the yarn tension substantially constant, a bobbin carrier, means for driving the same, and means operatively engaged by the yarn between the drag devices and the bobbin for interrupting the drive upon excessive tension on the yarn. 110

4. In a machine of the type described, an unraveling device comprising an upright vibratory rod and a drag sliding thereon and serving to set said rod into vibration on the lifting of the drag by the yarn through 120 increased tension on the yarn. 115

5. In an unraveling machine, a fabric support, a gravity drag device for unraveling the yarn from the fabric, a stationary guide over which the yarn passes from the drag 125 device, builder bar eyes to which the yarn passes from the guide, a plurality of vertical spindles carrying winding bobbins fed from the eyes of the builder bar, friction clutches for driving said spindles, horizontal 130

long arm levers controlling said clutches and means for suspending the long arms of said levers from the yarn at a point between the builder bar and said stationary guide whereby said levers may be actuated by the yarn to automatically halt the drive of the bobbin on abnormal tension on the yarn.

In testimony whereof I have signed my name to this specification, in the presence of two subscribing witnesses.

MAX ARTHUR MUELLER.
